UNITED STATES PATENT OFFICE.

LESTER R. WELLMAN, OF CHICAGO, ILLINOIS, ASSIGNOR TO FRIEDELEY VOSHARDT CO., OF CHICAGO, ILLINOIS, A CORPORATION OF ILLINOIS.

DESIGN FOR AN ARM FOR LIGHTING-FIXTURE PLATE.

Application filed December 22, 1921. Serial No. 524,315. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for an Arm for Lighting-Fixture Plate, of which the following is the specification, reference being had to the accompanying drawing, forming part hereof.

Fig. 1 is a side view of an arm for lighting fixture plate, showing my new design.

Fig. 2 is a plan view of the same.

I claim:

The ornamental design for arm for lighting fixture plate, as shown.

LESTER R. WELLMAN.
